STEP LADDER

Filed April 4, 1925

FIG. 1

FIG. 2

FIG. 3

Patented May 21, 1929.

1,714,028

UNITED STATES PATENT OFFICE.

FRED C. KNUTH, OF AURORA, ILLINOIS.

STEPLADDER.

Application filed April 4, 1925. Serial No. 20,688.

Artisans such as painters and paper hangers who must use step ladders find the standard step ladder inconvenient because of the variation of height of rooms and height of 5 men, the result being that they must work at a disadvantage upon surfaces that must be reached from ladders. The object of my invention is to overcome this by providing a step that may be applied to the ladder at 10 such place or level between the fixed or permanent steps with which it is provided as the workmen may find most advantageous. My invention consists in whatever is described by or is included within the terms or 15 scope of the appended claims.

In the annexed drawings:

Fig. 1 is a perspective view of a portion of a step ladder of standard or usual construction equipped with a step embodying 20 my invention;

Fig. 2 is a horizontal section;

Fig. 3 is a detail view in perspective of one of the step attaching and supporting clips.

My invention contemplates the application 25 to each side bar or vertical member of the step ladder of a clamp or clip which while easily applied and removed, nevertheless forms a rigid and safe support for a step member that extends between two clips and 30 these two clips are precisely similar in construction except that they are rights and lefts or reversed.

Referring in detail to what is shown in 35 the drawings, each clip comprises two L-shape members that are pivoted together by aligning eyes at the edges of the long and short legs respectively, so that they may be closed upon or about the four sides of the ladder side bar or vertical member, 10, the 40 long leg of one angle member, 11, lying against the inner side of said bar and the short leg lying next to the front edge of said bar, and the long leg of the other angle member, 12, lying against the outer side of said bar, 10, and its short leg lying against the rear edge of said bar, the pivot pin, 13, being situated at the back inner corner. The long leg of the angle member, 11, has sharp spurs 45 or projections, 14, adapted to penetrate the ladder vertical bar, 10, and the long leg of the other angle member, 12, has one or more similar spurs, one of such spurs, 15, being shown, to penetrate said ladder bar on the outer side and thus the clip is securely anchored 50 against downward movement under the weight of a man upon the step, 16, sup-

ported in the manner presently to be described by the two clips. The long leg of the angle member, 12, is extended a substantial distance to form a handle, 17, to enable 60 enough leverage to be exerted in applying the clip to the ladder bar as will cause the penetration of the spurs into said bar and said handle affords a convenient means of opening and closing the clip upon the bar. 65 When the clip is applied to the bar the two angle members are securely locked in bar engaging position as by means of an eye, 18, upon the short leg of the angle member, 11, that passes through a hole or slot, 19, 70 in the long leg of the angle member, 12, and a pin, 20, that is inserted through the projecting portion of the eye which pin is preferably a part of a hook, 21, that is pivoted to the angle member, 12, for convenient attachment and manipulation.

Each of the clips has upon its inner side a horizontally extending socket, 22, to receive an end portion of the step, 16, which need not be fastened in the socket although 80 it may be so fastened if desired.

The application and removal of my step to a desired portion of the ladder may be easily effected, for with the outer angle member, 12, unlatched, it may be swung on its 85 pivot until its short leg aligns with the long leg of the inner angle member, as shown on dotted lines in Fig. 3, and thus the two clips with the step mounted thereon may be passed between the two vertical side bars, 90 10, of the ladder.

My clips may be made of heavy sheet metal stamped into the desired shape and the various parts assembled and united by rivets or otherwise or the parts may be cast, the 95 inner angle member and the socket being thus formed in one piece and the outer angle member being formed of a single piece.

What I claim is:

1. A step attachment for ladders that have 100 permanent regularly spaced steps comprising clips, adapted to be applied to and removed from the ladder side bars and step supporting means carried by the clips extending between the side bars and supporting the step 105 in line with the permanent steps of the ladder, said clips wholly supporting said step independently of the permanent steps of the ladder.

2. A step attachment for ladders comprising 110 clips, adapted to be applied to and removed from the ladder side bars and step sup-

porting means carried by the clips extending between the side bars and supporting the step in line with the permanent steps of the ladder, each clip comprising inner and outer angle members hinged together and means to hold them in bar engaging position.

3. A step attachment for ladders comprising clips, adapted to be applied to and removed from the ladder side bars and step supporting means carried by the clips extending between the side bars and supporting the step in line with the permanent steps of the ladder, each clip comprising inner and outer angle members hinged together and means to hold them in bar engaging position, and a ladder engaging socket carried by the inner member.

4. A step attachment for ladders comprising

ing clips, each comprising members on opposite sides of the ladder, side bars and connections between said members extending from one to the other wholly at the front and back edges of the side bars, respectively, adapted to be applied to and removed from the ladder side bars, said clips having surfaces only for external engagement of the side bars and step-supporting means carried by each clip, and comprising opposite step-receiving sockets having bottom, side and top walls, each receiving a portion of the step to be supported thereby and engaging the step and restraining it from vertical and horizontal movement.

In testimony whereof I hereunto affix my signature.

FRED C. KNUTH.
